DAMPROOFING BUILDINGS

Allison G. Munro, Garden City, N.Y.

Application February 21, 1957, Serial No. 641,649

1 Claim. (Cl. 72—1)

This invention relates to dampproofing or waterproofing the walls of buildings and it has for its object to provide a novel and improved means for preventing moisture from seeping into the interior of modern buildings of the type having an outside shell or skin of glass, aluminum or the like in lieu of a conventional outer masonry wall.

Another object of the invention is to provide a simple and efficient means for draining moisture from within the wall space of buildings of the above type without altering the construction or appearance of the exterior shell of the building.

Various other objects and advantages will be apparent as the nature of the invention is more fully disclosed.

A number of methods and devices have been employed for draining moisture from inside the masonry walls of conventional buildings, the usual practice being to form drainage channels or weep holes at intervals in the mortar between the various layers of brick, hollow tile or the like constituting the outer face of the building.

However, the more modern buildings of the type with which I am here concerned have no such outer masonry walls. Instead, they have an outer shell or skin of glass, aluminum or the like composed of prefabricated panels which are simply attached to the frame of the building, for example by securing them to angle-irons which are embedded in the structural concrete at the various floor levels.

Buildings of the above type have an inner masonry wall which is built upon the concrete covering the spandrel beams at floor levels and is separated from the outer shell or skin by an air space. In dampproofing such a building I lay flexible moisture-proof flashing sheets between the concrete and the superimposed inner masonry wall in a manner which is conventional except that the flashing sheets are extended down the vertical face of the concrete to join a specially constructed flashing or plate confining a packing of insulating material which prevents condensation of moisture in the bottom of the air space at each floor level as hereinafter more fully described.

The various panels forming the outer shell of the building are set upright in elongated horizontal strips or frames which are supported by the concrete flooring and extend along the outside thereof below and outwardly of the inner masonry wall at each floor level. The said frames consist of elongated strips of metal having two spaced contiguous longitudinal channels. The shell-like panels constituting the outer skin or wall of the building are seated and sealed in the outer longitudinal channel of the frame and are thus separated from the inner masonry wall by an air space, while the inner longitudinal channel of said frame has a plurality of spaced weep holes in the bottom thereof for draining moisture from said air space downwardly upon the outside of the building.

Although the novel features which are characteristic of this invention are set forth more in detail in the claim appended hereto, the nature and scope of the invention may be better understood by referring to the following

2

description, taken in connection with the accompanying drawing forming a part thereof, in which a specific embodiment has been set forth for purposes of illustration.

In the drawing:

5 Fig. 1 is a vertical section through the wall of a building which is moistureproofed according to the present invention; and

10 Fig. 2 is a broken perspective view illustrating the double-channelled frame securing the shell-like panels of the building to the concrete flooring.

15 In the following description certain specific terms are used for convenience in referring to the various details of the invention. These terms, however, are to be interpreted as broadly as the state of the art will permit.

20 Fig. 1 shows a spandrel beam 1 supporting the concrete flooring 2 of a building, while 3 are the bricks or blocks which are laid in the usual way with intermediate courses of mortar 4 to form the inner masonry wall which is supported by the floor above the beam 1.

25 Flexible moisture-proof flashing sheets 5 are laid between the floor and wall, and have their respective end portions extending vertically upward against the inside of the wall and vertically downward against the outside of the concrete. These flashings may be of the type disclosed in my Patent #2,721,819, issued October 25, 1955.

30 The inside of the masonry wall may be coated with a suitable dampproofing adhesive 6, usually a tar-rubber composition, while 7 is the insulation over which the usual laths are laid in finishing the inside of the building.

35 The concrete flooring 2 supports an elongated horizontal metal frame or trough 8 having two continuous and contiguous longitudinal channels 9 and 10 extending along the outside of the floor below and outwardly of the masonry wall. The support for said frame 8 comprises a plurality of spaced L-shaped brackets 12 which are welded or bolted to plates 13 countersunk in the outer face of the concrete and are welded to the bottom of the frame 8 as illustrated.

40 The outer vertical wall or skin of the building comprises shell-like panels 14 which are seated in the outer longitudinal channel 9 of frame 8 and are sealed therein by suitable caulking 15, and are supported by angles 16 which are embedded in the concrete and are welded to the panels as shown in Fig. 1. The panels 14 are thus separated from the inner masonry wall by an air space 17.

45 The inner longitudinal channel 10 of frame 8 has a plurality of spaced weep holes 18 formed in the bottom thereof for draining moisture downwardly upon the outside of the building.

50 A longitudinal plate or flashing 19 adjacent the bottom of air space 17 has its lower edge portion turned down and secured as by welding to the vertical side of the inner channel 10 of frame 8, as shown in Fig. 1. The upper edge portion of plate 19 is seated in a longitudinal slot 20 formed in the vertical face of the concrete and is secured therein as by wooden wedges 21. The lower end of the flexible moisture-proof flashing 5 overlaps the plate 19, as shown in Fig. 1. A packing of insulating material such as glass wool 22 is confined between plate 19 and the outer vertical face of the concrete to prevent condensation of moisture in the bottom of the air space 17. In order to simplify the drawing, the plate 19 is omitted from Fig. 2.

55 Although a specific embodiment has been shown and described herein for purposes of illustration, it will be evident to those skilled in the art that the invention is capable of various modifications and adaptations within the scope of the appended claim.

70 The invention claimed is:

In a building structure having at a given floor level a

spandrel beam supporting a floor, an inner wall supported by said floor above said beam, means for preventing the ingress of moisture between said wall and said floor, an elongated horizontal frame having two spaced contiguous longitudinal channels supported by said floor and extending along the outside thereof and having the horizontal under surface of said frame beneath both of said channels exposed outside said building structure, and an outer vertical wall comprising shell-like panels seated and sealed in the outer longitudinal channel of said frame and separated from said inner wall by an air space, the inner longitudinal channel of said frame having a plurality of spaced weep holes in the bottom thereof for draining moisture from said air space downwardly upon the outside of the building.
